UNITED STATES PATENT OFFICE.

WILHELM HAMANN, OF CHARLOTTENBURG, GERMANY.

CLASP.

1,267,765.

Specification of Letters Patent. Patented May 28, 1918.

Application filed April 6, 1914. Serial No. 829,910.

To all whom it may concern:

Be it known that I, WILHELM HAMANN, painter, subject of the King of Prussia, residing at Charlottenburg, Hertzstrasse 7, 5 Prussia, Germany, have invented certain new and useful Improvements in Clasps, of which the following is a specification.

The present invention relates to a clasp for holding woven or other soft fabrics, such 10 10 as hose, curtains, hangings and the like by means of two loops engaging crosswise in each other.

The essential feature of the present invention consists in the fact that these loops are 15 of an oblong, oval or similar shape, which hereinafter shall be called "pear-shaped," and that the said loops are corrugated. Owing to these features it is possible to push the two loops, which may be considered as 20 turned around an angle of 180° relatively to each other, in such a manner crosswise in each other, that the smaller bend of the one loop will enter the larger bend of the other loop, while the corrugated parts engage in 25 such a manner beside and around each other, that, when seen from one side, appear as if partly twisted around each other, similar to a cord.

The object of such arrangement of the 30 clasp is that the material to be gripped, bears on as large a surface as possible or is gripped over a large surface. This will, on the one hand, afford an absolutely secure grip without the material being too severely worn, on 35 the other hand allow of an easy opening and closing of the clasp, and thus of an easy loosening and tightening or gripping of the material.

In the hitherto known devices, in which 40 likewise loops engaging crosswise in each other were employed, the hereinbefore mentioned advantages are not found to the same extent. All clasps of this kind hitherto disclosed grip the material only with a comparatively small part of the circumference 45 of the clasping members, wherefrom an extraordinarily high strain on the material and a rapid wear of the latter results, beside the fact, that the detaching and gripping 50 of the material requires a much more complicated manipulation than with the clasp according to the present invention.

In the accompanying drawing an embodiment of the present invention is exemplified. 55 Figures 1 and 2 are the one loop *a* in front and side elevation, respectively.

Figs. 3 and 4 are likewise front and side elevations respectively, but of the other loop *b*.

Figs. 5 and 6 are front and side elevations 60 respectively of the two loops *a* and *b* in closed position.

Figs. 7 and 8 are front and side elevations respectively of the complete clasp with the material clasped in it. 65

Fig. 9 is a side elevation of the clasp in an opened position.

In the drawing the one loop is marked *a*, the other, co-acting loop *b*. Each of these loops is attached to a stem, consisting of a 70 strip of sheet metal or the like, the loop *a* to the stem *c*, the loop *b* to the stem *d* respectively. The two stems are positively coupled together by a part *e*, so that when the part *e* is moved, the two loops *a* and *b* 75 are swung relatively to each other, as this is indicated in Fig. 9. The loops with their stems are, as evident from the drawing, pivotally hinged to the respective part *e*. The operation of the clasp is easily comprehensible with reference to the drawing. 80

In an opened position, as shown in Fig. 9, the material to be gripped is placed between the two loops, which are thereupon closed together, the smaller bend of the one loop 85 thereby engaging through the larger bend of the other loop. When the part *e* is turned upward, as indicated by dot-and-dash lines in Fig. 9 the loops engage crosswise in each other, and the respective material is clasped 90 or gripped between them, as shown in Figs. 7 and 8.

I claim:

1. A clasp comprising a support having two inter-engaging loops, one of said loops 95 being formed with an enlarged portion at one end and a smaller portion at the other end, and the other loop being reversely formed, said loops being fashioned in serpentine configuration so that the smaller 100 portion of the reversely formed loop may enter the enlarged portion of the other loop, and the smaller portion of the last mentioned loop may enter the enlarged portion of the reversely formed loop for fastening 105 the two loops together and to form a plurality of engaging surfaces along the sides of the clasp and at either end thereof for confining a fabric therebetween.

2. A clasp comprising a support having 110 two inter-engaging loops, one of said loops being formed with an enlarged portion at

one end and a smaller portion at the other end, and the other loop being reversely formed, said loops being fashioned in serpentine configuration so that the smaller portion of the reversely formed loop may enter the enlarged portion of the other loop, and the smaller portion of the last mentioned loop may enter the enlarged portion of the reversely formed loop for fastening the two loops together and to form a plurality of engaging surfaces along the sides of the clasp and at an end thereof for confining a

fabric therebetween, said reversely formed loop having a hook formed thereon in which the upper portion of the other loop is received for confining the fabric between the loops at their upper edges.

In testimony whereof I have affixed my signature in presence of two witnesses.

WILHELM HAMANN.
